UNITED STATES PATENT OFFICE

107,349

DESIGN FOR A DESK

James R. Clark, Rochester, N. Y., assignor to The National Cash Register Company, Dayton, Ohio, a corporation of Maryland

Application May 24, 1937, Serial No. 69,530

Term of patent 14 years

To all whom it may concern:

Be it known that I, James R. Clark, a citizen of the United States, residing at Rochester, in the county of Monroe and State of New York, have invented a new, original, and ornamental Design for Desks, of which the following is a specification, reference being had to the accompanying drawing, forming a part thereof, in which—

Fig. 1 is a perspective view showing the front, right side, and top of the desk.

Fig. 2 is a perspective view showing the back, left side, and top of the desk.

The design is characterized by its configuration as well as its ornamentation.

In its ornamentation, the design comprises

cabinet sections joined by a section having a supporting framework. The cabinet sections have plain tops outlined by bands of a distinguishing finish, and also have bases and drawer pulls of the same distinguishing finish. The cabinet sections, the joining section, and the supporting framework (shown stippled) are all finished alike, whereby the trim, including the bands, the drawer pulls, and the bases, being of a distinguishing finish, produce a contrast between the trim, the desk tops, and the main sections of the desk.

What is claimed is:

The ornamental design for a desk, as shown and described.

JAMES R. CLARK.
